[57] CLAIM

The ornamental design for a heat therapeutic belt, as shown and described.

DESCRIPTION

FIG. 1 is a top plan view of a heat therapeutic belt showing our new design, the bottom being plain and unadorned;

FIG. 2 is an end view thereof;

FIG. 3 is a rear elevational view thereof with the heat therapeutic belt flipped over; and

FIG. 4 is a front elevational view thereof.

The undisclosed rear portions of the therapeutic belt are plain and unornamented.
